Inventor:
Richard O. Oakley,
by Henry J. Neely,
His Attorney.

UNITED STATES PATENT OFFICE.

RICHARD O. OAKLEY, OF ST. LOUIS, MISSOURI.

WEATHER STRIP.

Application filed March 4, 1927. Serial No. 172,665.

My invention relates to weatherstrips and more particularly to metal weatherstrips adapted to be applied to casement windows, doors and the like for the purpose of rendering them weather tight.

Heretofore, such weatherstrips of this type as have been provided for use either have been ineffectual in operating to render the window or door weather tight or have been of such complicated form or shape as to make them too expensive in manufacture and in application to the structure to be weatherstripped.

The objects of my invention are to provide a weatherstrip for casement windows, doors or the like, which will effectually prevent water or air from entering between the door or window and the frame thereof and to provide such a weatherstrip which is cheap in manufacture and application.

An embodiment of my invention adapted for use on a casement window is shown in the accompanying drawings wherein similar letters are used to designate similar parts: Fig. 1 is a fragmentary elevation of my weatherstrip in place on the window; Fig. 2 is a section along the line 2—2 in Fig. 1; and Fig. 3 shows in detail one of the component parts of the weatherstrip.

Referring to the figures the weatherstrip comprises an upper member A attached to the window sash B by nails C or any other suitable means, and a lower member D attached to a part of the window frame E, preferably, by screws F. The upper member A has an outwardly projecting water shed G, and the longitudinally extending rib H which has the inner end, the end nearest the axis of the window, of the edge thereof bent downwardly, as is clearly shown at M in Figs. 2 and 3. The lower member D has the upwardly extending part J which terminates at its upper end in the inwardly projecting longitudinally extending rib K. Weep holes L may be provided in the lower member D so that any water condensing therein or collecting in the gutter thereof when the window is open may drain therefrom.

The ribs H and K on the upper and lower members, respectively, are preferably formed as shown with the edges thereof thicker than the base thereof so that the upper surface of the outer edge of the lower rib is normally in a plane above the plane of the lower surface of the upper rib, all for the

purpose as fully hereinafter set forth. Also, I prefer, that the member D be made of thick metal so as to be substantially rigid. However, the upper member A need not be as rigid as the lower member but, to the contrary, I prefer that it be formed of metal thin enough to give the rib H substantial resilience.

The operation of the weatherstrip embodying my invention is as follows:—The members A and D are attached to the window sash and the window frame, respectively, so that the rib K is slightly higher than the rib H, as shown in Fig. 2. When the window sash is swung on its hinges since the inner end of the rib H is bent downwardly, as described above, the inner end will be below the rib K and as the window is closed the inner end will be introduced under the rib K. As the closing of the window continues and since the rib H is resilient the whole rib H will be gradually introduced under the rib K, and when the window is in closed position the two ribs will be in interlocking engagement with the thick edge of the rib H lying next to and in contact with the thinner base of the rib K, and with the thick edge of the rib K lying adjacent to and in contact with the thinner base of the rib H, all as shown in Fig. 2. I prefer that the part of the upper member A just above the rib H be formed to follow the contour of the edge of the rib K and to be in contact therewith when the ribs are in interlocking engagement so that no water or air may flow inwardly past the top of the rib K. While, I prefer, that the thick edges of the ribs H and K are formed thick enough to form an interlocking engagement between the ribs, they are not to be so thick as to make such a tight interlocking engagement that when the window is opened they will not be easily carried out of engagement with one another. Also, I prefer that the edges of the ribs be rounded, as shown, so that when the window is closed the ribs will not butt but their shape will move the edges thereof past one another into an interlocking engagement, as described above.

In order that no water may flow between the upper member A and the face of the window sash B I prefer that the upper member A be bent slightly inwardly and embedded in the sash B whereby the joint between the upper member and the window sash B will be flashed. Also, I prefer that

the water shed G extend outwardly a substantial distance so that rain and wind to a great degree will be prevented from coming in contact with the rib K.

6. I do not intend to limit my invention to the exact details of construction shown in the drawings since it may be readily seen that the shape of the ribs H and K and of the other parts of the weather-strip may be varied within wide limits without deviating from the spirit of my invention as embodied in the claims set forth below. Further, my new and improved weatherstrip may be also used effectually at the top of the casement window and by forming the ribs H and K so that they may be easily moved into interlocking engagement the weatherstrip may be used along the side of the window opposite to the side which is hinged to the frame.

20. What I claim as new and desire to secure by Letters Patent, is:—

1. A weatherstrip for a casement window comprising a member attached to the sash of said window and a member attached to the frame thereof, each of said members having thereon a longitudinally extending rib, and said ribs and said members being positioned and formed with the upper surface of the outer edge of the lowermost rib being normally in a plane above the lower surface of the outer edge of the uppermost rib whereby said ribs will have an interlocking engagement with one another when said window is in closed position.

35. 2. A weatherstrip for a casement window comprising a member attached to the sash of said window and a member attached to the frame thereof, each of said members having thereon a longitudinally extending rib, each of said ribs having a thickened portion, and said ribs and said members being positioned and formed whereby said ribs will have an interlocking engagement with one another when said window is in closed position.

45. 3. A weatherstrip for a casement window comprising a member attached to the sash of said window and a member attached to the frame thereof, each of said members having thereon a longitudinally extending rib, each of said ribs being thicker at a part removed from the base thereof than at said base, and said ribs and said members being positioned and formed whereby said ribs will have an interlocking engagement with one another when said window is in closed position.

55. 4. A weatherstrip for a casement window comprising a member attached to the sash of said window and a member attached to the frame thereof, each of said members having thereon a longitudinally extending rib, one of said ribs having the inner end of the edge thereof bent away from the other of said ribs, and said ribs and said members being positioned and formed whereby when

said window is closed the said ribs will be brought into an interlocking engagement with one another.

5. A weatherstrip for casement windows comprising a member attached to the sash of said window and a member attached to the frame thereof, each of said members having thereon a longitudinally extending rib, said ribs being thicker at a part removed from the base thereof than at said base, one of said ribs having the inner end of the edge thereof bent away from the other of said ribs, and said ribs and said members being positioned and formed whereby when said window is closed the said ribs will be brought into an interlocking engagement with one another.

6. A weatherstrip for a casement window comprising an upper member attached to the sash of said window and a lower member attached to the frame thereof, each of said members having thereon a longitudinally extending rib, said upper member having a water shed above the rib thereof, and said ribs and said members being positioned and formed with the upper surface of the outer edge of the lowermost rib being normally in a plane above the lower surface of the outer edge of the uppermost rib whereby said ribs will have an interlocking engagement with one another when said window is in closed position.

7. A weatherstrip for a casement window comprising an upper member attached to the sash of said window and a lower member attached to the frame thereof, each of said members having thereon a longitudinally extending rib, said upper member having a water shed above the rib thereof, said ribs and said members being positioned and formed whereby said ribs will have an interlocking engagement with one another when said window is in closed position, and said upper member having a portion thereof above said rib arranged to follow the contour of the edge of the rib on said lower member when said ribs are in interlocking engagement.

8. A weatherstrip for a casement window comprising an upper member attached to the sash of said window and a lower member attached to the frame thereof, each of said members having thereon a longitudinally extending rib, the rib on said upper member having the inner end of the edge thereof bent downwardly, and said ribs and said members being positioned and formed whereby when said window is closed the rib on said upper member will be introduced under the rib on said lower member and said ribs will be brought into an interlocking engagement with one another when said window is in closed position.

9. A weatherstrip for a casement window comprising an upper member attached to the

- sash of said window and a lower member attached to the frame thereof, each of said members having thereon a longitudinally extending rib, the rib on said upper member having the inner end of the edge thereof bent downwardly, said ribs and said members being positioned and formed whereby when said window is closed the rib on said upper member will be introduced under the 5 rib on said lower member and said ribs will be brought into an interlocking engagement with one another when said window is in closed position, and said upper member having a water shed arranged above said ribs 10 and having a portion thereof arranged to follow the contour of and contact with the edge of the rib on said lower member when said ribs are in interlocking engagement.
10. A weatherstrip for a casement window comprising an upper member attached to the sash of said window and a lower member attached to the frame thereof, said upper member having a longitudinally extending rib thereon, said lower member extending 15 upwardly past the break between said sash and said window frame and having at its upper end an inwardly projecting longitudinally extending rib, and said members and said ribs being positioned and formed 20 whereby said ribs will have an interlocking 25 engagement with one another when said window is in closed position.
11. A weatherstrip for a casement window comprising an upper member attached to the sash of said window and a lower member attached to the frame thereof, said upper member having a longitudinally extending rib thereon with the inner end of the edge thereof bent downwardly, said lower member extending upwardly past the break between 30 said sash and said window frame and having at its upper end an inwardly projecting longitudinally extending rib, said ribs being thicker at the edges thereof than at the base thereof, said ribs and said members being positioned and formed whereby when said window is closed the rib on said upper member will be introduced under the rib on said lower member and said ribs will be brought into an interlocking engagement 35 and having a portion thereof arranged to follow the contour of and contact with the edge of the rib on said lower member when said ribs are in interlocking engagement.
